FIG. 3

Eber H. Van Valkenberg Inventor

By Herbert E. Smith

Attorney

UNITED STATES PATENT OFFICE.

EBER H. VAN VALKENBERG, OF MONROE, WASHINGTON, ASSIGNOR OF ONE-HALF TO
OSCAR SILVERSTEIN, OF SPOKANE, WASHINGTON.

AIRSHIP.

Application filed April 27, 1925. Serial No. 26,082.

To all whom it may concern:

Be it known that I, EBER H. VAN VALKENBERG, a citizen of the United States, residing at Monroe, in Snohomish County and State 5 of Washington, have invented certain new and useful Improvements in Airships, of which the following is a specification.

The present invention relates to improvements in airships of the dirigible or navigable balloon type, and particularly to the 10 structure of the gondola or car suspended below the body of the airship.

The primary object of my invention is the provision of means whereby the ship 15 may be ballasted to insure a horizontal position for cruising, as well as to bring the ship to an inclined position with its forward or bow end up or down as desired when coming to an anchorage or rising in the air. Such ballasting may be necessary to compensate 20 for changes in the position of the crew, and displacements or redistribution of other loads or weights carried by the air ship.

For this purpose the car is suspended below 25 the body of the ship for longitudinal movement relative to the body of the ship, and pneumatic or other motive fluid means are provided for controlling the shifting of the car with relation to the ship.

The invention consists in certain novel 30 combinations and arrangements of parts as will hereinafter be more fully pointed out and claimed.

In the accompanying drawings I have illustrated 35 one complete example of the physical embodiment of my invention wherein the parts are combined and arranged in accordance with the best mode I have thus far devised for the practical application of the principles of my invention.

Figure 1 is a view in side elevation showing 40 a portion of an aircraft or airship with the car suspended therefrom and illustrating the general arrangement of parts of my invention.

Figure 2 is a longitudinal vertical sectional view of part of the car showing the 45 pneumatic control mechanism for the car.

Figure 3 is a cross section through the car 50 and a fragment of the aircraft showing the attachment means and pneumatic control mechanism.

The buoyant body of an airship or air 55 craft is designated by the numeral 1, and along the sides of the keel of the ship are

carried longitudinally extending parallel spaced flanged rails 2 forming tracks of suitable length and attached in suitable manner to the body of the ship.

The gondola or car 3 which is of suitable 60 type is located beneath the body of the ship and provided with an upper longitudinally extending frame 4 fixed along its upper side edges and forming part of the frame structure of the car.

Rollers 5 journaled in supporting brackets 6 on the frame 4 are spaced at suitable intervals and carried by the frame of the car to suspend the latter on the parallel tracks 2 of the body of the ship, in order 70 that the car may be moved fore and aft with relation to the ship for the purpose of stabilizing the ship. By thus moving or adjusting the car with relation to the ship the weight of the car is imposed at selected 75 points on the ship to hold it in horizontal position or for the purpose of changing its position with relation to the horizontal plane.

Fore and aft propellers 7 and 7 are carried 80 by the car, and power is applied thereto in approved manner for the propulsion of the ship in usual way.

The car is adjusted longitudinally of the 85 ship by pneumatically operated, duplex mechanism carried by the car and controlled from within the car for co-action with the ship. For this purpose an air plant or compressor is indicated at 9 having a pair of motive fluid pressure pipes 10 and 11 extending therfrom for supplying compressed air to the air cylinders 12 and 13 respectively. Control valves 14 and 15 of the three-way type are provided in these supply 90 pipes to control admission of compressed air to one side of the operating mechanism and at the same time permit withdrawal of air from the other side of the mechanism, as will be described.

The cylinders are arranged in alignment 100 extending longitudinally of the ship and car, and they are supported in the frame 4 of the car at the top thereof, which frame is fashioned with a depression 16, and transversely arranged straps 17 to hold the cylinders 12 and 13 against longitudinal or lateral displacement.

Each cylinder is provided with a piston, 105 as 18 and 19 having rods 20 and 21 extending through suitable boxes in the outer ends 110

of the aligned cylinders, and the ends of the rods are pivotally connected at 22 and 23 to hangers 24 and 25. These hangers are bolted or otherwise rigidly secured along the 5 keel line of the ship and form fulcrums or abutments against which pressure is selectively applied for moving or adjusting the car.

The outer heads of the cylinders are provided with outwardly opening spring-pressed vent valves 26 to permit egress of air from the outer ends of the cylinders when motive fluid pressure is applied, as at the working side of the piston 18 from pipe 10. The cylinders are also provided with small inwardly opening spring pressed equalizing valves 27, one in each of the outer ends of the cylinders.

It will be apparent that the piston 18 forms a stationary abutment for motive fluid pressure admitted to the cylinder against the working side of the piston, and the pressure is exerted against the working side of the piston and the adjacent head of the cylinder to move the car to the right or toward the stern of the ship in Figures 1 and 2. By this movement air is forced out of the cylinder through valve 26 at the left of the piston-abutment and pressure of air between the abutment and the right head of the cylinder moves the cylinder and car to the right. When motive fluid pressure is admitted to the left or working side of the piston 19 in the cylinder 13, the reverse movement takes place, and the cylinder and car move to the left. The control valves 14 and 15 for the motive fluid are preferably three-way valves and these two valves are properly manipulated when shifting the car in either 30 direction to supply motive fluid to the working side of one piston-abutment and relieve pressure at the working side of the other piston-abutment.

Thus the two control valves are simultaneously manipulated in such manner that the motive fluid pressure may be applied in one cylinder to positively shift the car longitudinally of the ship and the withdrawal of air from the other cylinder is controlled in 45 relation to the operation of the working cylinder for a selected quick shifting of the load, or for a slower shifting of the load or car and with minute accuracy of adjustment in equilibrating the ship.

50 From the above description it will be apparent from an inspection of my drawings

that I have provided the ship with means whereby the objects of my invention may be carried out with facility, reliability and accuracy for proper control of the ship.

Having thus fully described my invention, what I claim as new and desire to secure by Letters Patent is—

1. The combination with an airship and a longitudinally movable car suspended thereon, of a stationary abutment carried by one of said members, and motive fluid actuated means carried by the other member for co-action therewith for relatively adjusting said members. 65

2. The combination with an airship and a longitudinally movable car suspended thereon, of a motive fluid cylinder carried by the car and a stationary piston head forming an abutment carried by the airship, and means for controlling the admission and exhaust of motive fluid to and from said cylinder for relatively adjusting the airship and car. 75

3. The combination with an airship having spaced longitudinally extending track rails and a car having supporting rollers on said track rails, of a motive fluid cylinder carried by the car and means for controlling the admission and exhaust of motive fluid to 80 said cylinder, and a stationary piston head forming an abutment in the cylinder carried by the airship. 85

4. The combination with an airship having spaced longitudinally extending track rails and a car having supporting rollers on said rails, of a motive fluid cylinder carried by the car and means for controlling the admission and exhaust of motive fluid to 90 said cylinder, a piston head forming an abutment in the cylinder, a rod connected to the head, and an anchoring device on the airship connected to one end of said rod. 95

5. The combination with an airship having spaced longitudinally extending track rails and a car having supporting rollers on said rails, of a pair of aligned cylinders carried by said car and an air compressor connected to said cylinders, valves for controlling admission and exhaust of air to and from said cylinders, a pair of piston heads forming abutments in said cylinders, and means for anchoring the respective piston heads to said airship. 100 105

In testimony whereof I affix my signature.

EBER H. VAN VALKENBERG.
